UNITED STATES PATENT OFFICE.

ALBERT SCHWARZ, OF CINCINNATI, OHIO.

PROCESS OF MAKING SIGNS.

Application filed May 26, 1926. Serial No. 111,871.

My invention relates broadly to processes of making signs, and particularly to processes of making transparent signs.

It is the object of my invention to make a transparent sign, which shall consist in a backing member, having an opaque coating thereon, which shall have uncoated portions, through which a light will be visible. It is further my object to make such a sign in a novel manner, which not only enables me to make a sign having a neat appearance, but also, which can be very inexpensively made.

Referring to the drawings in which I have illustrated a preferred type of sign in which the several figures illustrate the steps in the process of manufacture:—

Figure 1 is a front elevation of the sign enclosed in a frame.

Figure 2 is a perspective view of a portion of the flexible backing sheet from which the sign is made.

Figure 3 is a front elevation of the backing sheet, after the application of the layer of paint.

Figure 4 is a front elevation of a portion of the finished sign transparency.

Figure 5 is a perspective view showing the transparency enclosed in an illuminative casing.

Figure 6 is a section taken along the lines 6—6 in Figure 1.

I prefer to use as a backing sheet, a web of resilient transparent material such as is indicated at 1 in Figure 2. The material illustrated, is known in the trade as cello-glass, and consists of a web of wire screen to which has been applied a coating 2, of some transparent material such as celluloid.

Although cell-o-glass forms a very desirable backing sheet because the wire of the screening provides a flexible and very strong support for the transparent filler of celluloid, other suitable materials which have similar functions may also be used with satisfactory results.

The flexible sheet of backing is then painted with a coat 3 of suitable paint, which covers the backing in a thin transparent layer, through which selected areas may be revealed. The paint is then allowed to dry, and the sheet or web is then printed with a solid layer 4 of paint, preferably from arcuate soft composition roller, having recesses therein, which outline the various figures or marks which are to be displayed. In the illustrations, letters are the illuminative objects

which are to be displayed. In the portions outlined by the recesses in the die, the paint coating, which as has been noted, has been allowed to dry, will have a glossy unadhesive surface. While the paint is still wet, a layer 5 of finely divided powder, such as granulated smalt or block of any desired color, is sprinkled or dusted on, and the coating of the powdered material will adhere to the background part of the sign and form a permanent background through which the rays of light will not shine with the same intensity as through the dried areas, to which none of the granulated material has adhered.

After the outer coating of granulated material has thoroughly dried into the paint, the flexible sheet may be bound in a frame such as is indicated at 6, and electric light globes or other sources of illumination may be arranged so as to shine through the letters or figures.

The use of a flexible sheet is particularly desirable because it will feed through rollers so that the sheets may be wound on a spool and then fed between rollers in a rotary press. This enables signs, such as disclosed, to be made in a continuous web which greatly reduces the cost of decorating.

While signs made in accordance with my invention are particularly adapted for illuminative use, the signs even without sources of light behind the transparency are brilliant and set out the advertising matter displayed in a very attractive manner.

Modifications in which different materials and different colors other than those particularly specified are employed, are within the scope of my invention. While I have shown a sign for purposes of illustration, which has the advertising matter outlined in a positive manner, it will also be within the scope of my invention to use the invention in what may be called a negative manner, in which the background will be transparent and illuminated, and the letters or marks will be covered with the coating of granular or powdered material.

Having thus described my invention what I claim as new and desire to secure by letters patent is:—

1. A process for making transparencies which consists in filling the meshes of a wire cloth sheet with translucent material, coating the filled sheet of wire cloth with a translucent pigmented body of cellulose character, when the said coating is dry printing the sheet with

a second pigmented coating in desired areas to give the desired visual impression, and finally, while the second coating is tacky, applying thereto an opaque powder which does not adhere to the first coating, for the purpose described.

2. A process for printing on wire cloth

which consists in imposing on the wire cloth a pigmented coating which covers the wires and the spaces between them and is translucent, and then printing, after the first coating is dry, a pigmented pattern coat which is then dusted with an opaque powder.

ALBERT SCHWARZ.
